ATTORNEY.

UNITED STATES PATENT OFFICE.

HAROLD O. BIGNEY, OF ATTLEBORO, MASSACHUSETTS, ASSIGNOR TO SIDNEY O. BIGNEY, OF ATTLEBORO, MASSACHUSETTS.

DESIGN FOR A CIGARETTE-CASE.

41,806.

Specification for Design.

Patented Sept. 26, 1911.

Application filed April 10, 1911. Serial No. 620,236. Term of patent 3½ years.

To all whom it may concern:

Be it known that I, HAROLD O. BIGNEY, a citizen of the United States, residing at Attleboro, in the county of Bristol and State of Massachusetts, have invented a certain new, original, and ornamental Design for a Cigarette-Case, of which the following is a specification.

In the accompanying drawings which form a part of this specification, the figure is a front elevation of a cigarette case embodying my new design.

I claim,

The ornamental design for a cigarette case, as shown.

HAROLD O. BIGNEY.

Witnesses:

HORATIO E. BELLows,
GEORGE H. McLAUGHLIN.
